UNITED STATES PATENT OFFICE

FRANZ HUEBNER, OF ZWITTAU, CZECHOSLOVAKIA, ASSIGNOR TO SMYRNA AUTOMAT
G. M. B. H., OF ZITTAU, SAXONY, GERMANY

MACHINE FOR THE MANUFACTURING OF KNOTTED CARPETS AND THE LIKE

Application filed September 16, 1930, Serial No. 482,337, and in Austria August 27, 1929.

This invention relates to devices for the production of knotted carpets and the like. The manufacture of carpets, covers, and the like in which the pile is formed by the knotting of short tufts into a system of ground threads, in particular of the so-called Persian and Turkey carpets, has been carried out until recently exclusively by hand. Only in the last few years has it become possible to manufacture knotted carpets of this order mechanically, and this has been accomplished by means of machines which work entirely automatically and in which the formation of the pattern is effected by means of a jacquard machine.

The exceedingly complicated construction of the hitherto employed carpet knotting machines implies unusually high initial costs and charges for amortisation; the tending of these machines is very laborious and costly, and their employment is only remunerative when each carpet pattern and each shape is manufactured in very large numbers. This implies, however, the loss of the "individuality" of each single carpet which clearly constitutes the most valuable feature of the hand-knotted oriental carpets.

It has already been proposed to manufacture knotted carpets by arranging for the selection of the pile threads to be carried out by hand and for the knotting of these threads into the warp threads of the ground texture to be effected by machinery. The hitherto known devices for the carrying out of this semi-automatic method of manufacturing knotted carpets have not been practically useful, and have never in fact been put into practice, mainly for the reason that the mechanism for the selection and setting in position of the pile threads before knotting required far too great an expenditure of energy to enable them to be actuated rapidly by hand, or else was so slow in operation that it provided no advantage in comparison with hand-work pure and simple.

The present invention provides a device for the manufacture of knotted carpets and the like with Turkey or Persian knots which is very simple and cheap, easy to mount on any loom suited for the manufacture of

heavy texture, and capable of being actuated by hand at high speed and without appreciable expenditure of energy. The essential feature of the invention is that adjustable setters are provided for bringing the pile threads independently of each other to within the grasping range of the pile-thread withdrawing nippers, and that the act of operating one of these setters to place any one of the pile threads in the sphere of operation of the withdrawing nippers sets in motion the mechanism for the formation of the knots and for the feeding forward of the knotting device.

The accompanying drawings illustrate, as a constructional example of the invention, a carpet knotting loom with a horizontal warp and a single knotting device associated therewith. Fig. 1 shows in perspective a cross-section of the loom together with the arrangement for the mounting of the knotting device; Figs. 2-5 show the disposition of the knotting device on the loom and also the arrangements for the forward feeding movement of the knotting device in the direction of the weft, in front elevation, plan, and two side elevations respectively; Fig. 6 shows a detail of these latter arrangements on an enlarged scale; Fig. 7 shows, in the same view as Fig. 2, the knotting device together with a pile thread setter attached thereto; Fig. 8 shows the pile thread setter in side elevation, that is to say as seen from the breast beam of the loom, with one pile thread guide shown in the operative position; Fig. 9 shows the pile thread setter in plan.

To the framework 10 of a loom there is attached at each side an upright 11. Each of these uprights 11, only one of which is shown in the drawings, is provided with a vertical rail 12 on which a cradle-arm 13 is slidably mounted. The two cradle-arms 13 located at the ends of the loom are connected together by means of two rails 14 and 15 to form a single framework. Upon the rails 14 and 15, which extend across the entire breadth of the loom, there runs on rollers 16 (Figs. 2, 3, 4, and 5) a carriage bearing the knotting device. To the cradle-arm 13 there is attached a short link 17 which is connected to the end

65

70

75

80

of a lever 18 pivoted on the upright 11 (Fig. 1). On the lever 18 there is articulated a tension rod 19 which is connected at its other end to a double-armed lever 20; this lever 20 can be tilted about its pivot 23 by means of a connecting rod 21 and a crank arm 22, whereby the carrying framework of or the knotting device formed by the arms 13 and the rails 14 and 15 is raised and lowered. In this manner the carriage which runs on the rails 14 and 15 and which conveys the knotting device and other mechanism can be lifted out of the path of the slay 24, so that the latter can leave the extreme rearward position in which it is shown in Fig. 1 to carry out its blow, as soon as the knotting device has completed a row of knots and a weft thread has been inserted in the ground texture.

The knotting device proper, that is to say the system of withdrawing nippers, drivers, shears, and knotting pincers together with the actuating mechanism (eccentric sheaves, cranks, etc.) by means of which a length of pile thread is drawn forth, cut off, and knotted into the warp does not form part of the invention. Any one of the many known knotting devices can be employed, provided the same can be mounted on a framework or carriage running on the rails 14, 15 and be moved progressively across the entire breadth of the loom in the direction of the weft. Such known knotting devices are shown in U. S. Patents Nos. 1,164,117, 1,193,229, 843,358 and others. In Figs. 2-5 the whole of the knotting mechanism proper is indicated by the rectangle denoted by K. The devices serving for the mounting and forward movement of the knotting device K are shown in Figs. 2-6.

The wheels or rollers 16 running on the rails 14, 15 are connected together in pairs by means of axles 25. The two axles 25 are in turn connected together by means of a rod 26 on which there is pivotally mounted a stirrup 27 which carries the knotting device K. The knotting device K is thus capable of being swung about the axis 26 in the direction of the arrow I (Figs. 4 and 5), that is to say in the direction of the length of the loom.

After the knotting of each knot into the warp the knotting device K must be moved forward to the extent of the breadth of one knot, that is to say the extent of the distance from the middle of one knot to the middle of the next knot in the direction of the weft (arrow II, Figs. 2, 3). This extent of feed movement corresponds, since a Persian or Turkey knot is knotted into two adjacent warp threads, to two spaces between the dents 28 of the reed 29 (Fig. 2).

During the formation of a knot the knotting device K must clearly remain stationary and be held in position. The reed 29 serves both for the holding of the knotting device in position and also as a ratchet bar for controlling the extent of the forward movement

of this device after the completion of each knot. On the frame K carrying the entire knotting mechanism there is provided a downwardly projecting stirrup-shaped member 30 (Figs. 2 to 5) to which a short toothed bar 31 is rigidly attached. The teeth of this toothed bar 31 which will hereinafter be referred to as the "fixed advancing foot", correspond exactly to the spacing of the dents 28, of the reed 29, and during the knotting process this fixed advancing foot 31 engages in the reed 29 and thereby prevents the displacement of the knotting device K in the direction of the weft (arrow II, Figs. 2 and 3).

The position of the axle of suspension 26 in relation to the slay 24 (in the extreme rear position) is so determined that the centre of gravity of the knotting mechanism together with all the parts suspended from the axle 26 is not directly beneath the axle 26 but slightly to the side of the position of equilibrium of the entire suspended system, and is shown somewhat to the right of the latter in Fig. 3. In this manner a small component of the weight of the entire system suspended from the axle 26 is brought to bear on the reed 29 (in the opposite direction to that of the arrow I in Fig. 4), in the manner of a pendulum when displaced from the position of equilibrium, and holds the fixed advancing foot 31 firmly in contact with the reed.

There is further attached to the frame carrying the knotting mechanism a second short toothed bar 32 which is movable in regard to the knotting device both in a direction at right angles to the surface of the reed 29 (arrow III in Fig. 4) and also in a direction parallel to the weft (arrow II, Figs. 2, 3). The spacing of the teeth of this second toothed bar 32, hereinafter termed the movable advancing foot, likewise registers with that of the reed 29. In the feeding forward of the knotting device to the extent of the width of a knot the movable advancing foot 32 first carries out a movement relatively to the reed 29, so that it swings the knotting device about the axle 26 in the direction of the arrow I (Fig. 4) and presses this device away from the reed to such an extent that the teeth of the fixed advancing foot 31 are brought out of engagement with the reed 29; the teeth of the movable advancing foot 32 are then alone in engagement with the reed. A movement equal to the length of the feed stroke of the knotting device K is then imparted to the movable advancing foot 32 in a direction parallel to that of the weft (arrow II, Figs. 2 and 3), whereby the whole of the system running on the wheels 16 including the knotting device K is fed forward to the extent of the distance between two alternate dents 28. A short movement in the opposite direction to that of the arrow I (Fig. 4) is then imparted to the movable advanc-

ing foot 32, so that the frame K carrying the knotting mechanism is again pressed against the reed 29 by the influence of the above-mentioned small component of its weight, and the fixed advancing foot 31 is again brought into engagement with the reed. The knotting device K is thus again locked against displacement in the direction of the weft, and is in readiness for the tying of the next knot.

10 The driving of the movable advancing foot 32 can clearly be effected in a number of ways. In the constructional example shown in the drawings (Figs. 2-6) this foot 32 is attached to a cross-bar 33 articulated to the ends of two 15 links 34 and 35; these links are coupled by means of universal joints to the axle 26 and derive from the main driving shaft 36, which drives the entire knotting mechanism, the 20 movements necessary to actuate the movable advancing foot 32 in the manner described above. The link 34 is driven by an eccentric sheave 37 attached to the main shaft 36 (arrow III, Fig. 4). The peripheral surface 25 of this eccentric sheave 37 is not cylindrically but spherically shaped, so that the eccentric rod can also carry out a slight lateral movement (arrow II, Figs. 2 and 3). The link 35 is actuated by an eccentric sheave 39 30 through an eccentric rod 40. The eccentric sheave 39 is mounted on a vertical shaft 41, and is driven from the main shaft 36 through the intermediary of a bevel gear 42, 43 comprising a known type of reversing coupling 35 44 adapted to reverse the shaft 41 and sheave 39. The eccentric rod 40 is provided with a slot 45 (Fig. 3) with which there cooperates a link block 46 attached by means of a pivot pin 47 to a sliding member 48. This sliding 40 member 48 is adjustably mounted on a projecting portion 49 of the frame K carrying the knotting mechanism, and is adapted to be secured in position by means of two screws 50 (Fig. 3). The eccentric rod 40 thus carries out not only a reciprocating movement 45 corresponding to the throw of the eccentric pin 47 as pivot. By means of this combination of swivelling and reciprocating movements the link 35 and thus also the cross-bar 33 and the foot 32 are caused to carry out the above-described movements in respect to the reed 29 effecting the feed of the entire 55 knotting device.

According to the setting of the reversing coupling 44 controlling the direction of rotation of the shaft 41 the knotting device K is fed towards the left or towards the right. The knotting device therefore does not require to be returned to the starting position after the completion of a row of knots from left to right, but can be set, by actuation of the reversing coupling 44, to be fed in the 60 opposite direction, that is to say from right

to left. For this purpose the teeth of the fixed and movable advancing feet 31 and 32 are provided with symmetrically shaped flanks (Fig. 6).

In consequence of the fact that, in accordance with the invention, the reed of the carpet knotting loom serves as ratchet bar for the feeding forward of the knotting device the closeness (setting) of the knots can easily be varied. It is merely necessary, as in the alteration of the warp setting on ordinary looms, to change the reed 29 for a new reed of the required setting. The stroke of the movable advancing foot 32 must, however, be adapted to the spacing of the reed 29, which can easily be accomplished by the shifting of the pivot 47 of the eccentric rod 40 by means of the sliding member 48 (Fig. 3). Further the fixed and movable advancing feet 31 and 32 must be replaced by others the spacing of the teeth of which registers with that of the new reed 29. To this end the advancing feet 31 and 32 are interchangeably attached to the parts 30 and 33.

Since the reed 29 has to serve as ratchet bar for the feeding forward of the knotting device, and since the dents are thereby submitted to a certain amount of strain these dents 28 are supported from the side opposite the advancing feet and along the points of application of these feet by means of a batten or bar 51. This batten 51 is bound to the dents 28 by a thin wire 52 (Fig. 2).

From the main driving shaft 36 not only the drive for the feeding forward of the knotting device K is derived, but also the actuation of the pile thread withdrawing nippers, of the shears which cut off a length of the withdrawn pile thread, of the device which separates out two warp threads, and also of the knotting pincers proper which knot the severed pile tuft into the two separated warp threads. All these devices, as also the entire system of shafts, gear wheels, eccentric sheaves, etc. serving to drive the same are shown in Fig. 7 which is a similar front elevation to that shown in Fig. 2 but, since they do not form part of the present invention, are not denoted by reference characters, with the exception of the pile thread withdrawing nippers which are denoted by the number 53.

The main shaft 36 is preferably driven by means of a small electromotor (not shown) which is likewise mounted on the carriage, for example on a projecting portion of the frame K, and therefore participates in the forward feed movement of the knotting device (arrow III, Figs. 2 and 3). The drive of the main shaft 36 can, however, be effected by a shaft set in rotation in any desired manner, e. g. by means of a pedal, the movement of which is transmitted by means of a belt, chain, or the like to a wheel keyed on the main shaft 36.

The knot-forming mechanism and the

mechanism for the feeding forward of the knotting device are set in motion by the actuation of the pile thread setter, that is to say by the act of bringing the pile thread next required to be knotted into position within the grasping range of the pile thread withdrawing nippers 53. This purpose is served by the arrangement of parts now to be described with reference to Figs. 7, 8, and 9.

10 To the frame K carrying the knotting mechanism there is attached a frame 54 (Figs. 7-9) in which, on a rail 55 (Figs. 8 and 9), a number of angularly bent levers 56 are movably mounted in the manner of the 15 keys of a typewriter. These levers 56 serve for the guidance of the pile threads derived from the variously coloured pile thread bobbins. The system of pile thread bobbins is also disposed on the carriage running on the 20 rails 14, 15, so that it participates in the forward feed movement of the knotting device. As will be seen from Fig. 7 there is attached to the stirrup-shaped member 27 which carries the frame K an angularly bent rod 57 which is fitted at its lower end with a plate 58 or the like upon which are arranged a 25 number of perpendicular spindles on which the variously coloured pile thread bobbins are placed. Above the spindles 59 there is mounted on the carrying rod 57 a guide frame 60 in which guiding eyes 61 are provided for the pile threads 64. Each of the 30 setting levers 56 is provided at its upper end with a guiding eye 62 (Figs. 7 and 8), and its lower end with a tubular eye 63. The pile threads 64 derived from the bobbins 64' thus pass consecutively through the eyes 61, 62, and 63. The eyes 63 are provided in a known manner with a small braking spring which 35 exercises a slight pressure on the pile threads drawn therethrough.

40 When the setting levers 56 are in the position of rest (Fig. 7) their lower ends, and thus also the ends of the pile threads 64 projecting slightly beyond the eyes 63, are at a distance from the knotting mechanism.

45 With each of the setting levers 56 there cooperates a key lever 65 which acts by means of a pin 66 (Fig. 8) on the one arm of the appropriate setting lever 56. The keys 67 are arranged in juxtaposition, as shown in Figs. 50 7 and 8, in the manner of the key-board of a typewriter. The depression of one of the keys 67 causes the appropriate setting lever 56 to be tilted into the position shown in Fig. 55 8, in which position the lower end of the setting lever together with the end of the pile thread 64 projecting slightly from the eye 63 is within the grasping range of the pile 60 thread withdrawing nippers 53, which latter having already been brought into the operative position. The pile thread withdrawing 65 nippers 53 carry out, at the start of each operating cycle, a tilting movement (in Fig. 7 towards the left), so that they come into a

position immediately in front of the final position of the eye 63 of the tilted lever 56 (Fig. 8).

60 All the setting levers 56 are so mounted and guided that their lower ends with the 70 guiding eyes 63 are brought into precisely the same position (as in the case of the type-levers of typewriters). A stop 68 limits the stroke of the setting levers 56 (Fig. 8) and a funnel-shaped guide 69 (Fig. 9) ensures that 75 the ends of the setting levers 56 always come into precisely the same position in front of the pile thread withdrawing nippers when the latter are in the operative position.

80 The following arrangement is made for the purpose of causing the mechanism for forming the knots and for feeding the knotting device forward to be set in motion by the act of depressing one of the keys 67 which sets one of the pile threads 64 in position within 85 the grasping range of the pile thread withdrawing nippers 53.

85 When the knotting device is directly driven by means of a small electric motor the latter can be started by the depression of any 90 one of the keys 67; this motor is then switched off by the returning of the key and the setting lever 56 to the position of rest. The switching on and off of the current can be effected, for example, by the closing of 95 contacts (not shown) by the depression of any one of the keys 67 and the separation of the same by the returning of this key to the position of rest.

100 A preferable arrangement is, however, to place between the main shaft 36 and the driving shaft 70 (Figs. 2 and 7), which latter may be driven in any desired manner, a clutch 71 which is engaged by the depression of any one of the keys 67 and disengaged by the returning of the same to the position of rest. Alternatively this clutch 71 can be en-

105 gaged and disengaged electrically by the inclusion of an electromagnet adapted to actuate the movable part of the clutch and to be supplied with current when a key is depressed and deprived of current when this key returns to the position of rest. It will be clear, however, that the engaging and disengaging of the clutch 71 can also be effected 110 mechanically in dependence on the actuation of any one of the keys 67. All the key levers 65 can for example cooperate with one and the same member constructed in the manner of the known bridges of typewriters, by 115 means of which member the clutch 71 is adapted to be engaged and disengaged. In Fig. 7m denotes the electric contact or actuating member in connection with the key levers and n the electrical or mechanical connection to the clutch 71.

120 When a key 67 is depressed and a pile thread thereby set within the range of the pile thread withdrawing nippers all the other pile threads 64 remain motionless. The set- 125

ting of the pile threads is thus very easily effected by a tap of the finger, even with a very large number of threads.

The main shaft 36 set in rotation by the depression of one of the keys 67 then effects mechanically all the further steps necessary for the formation of the knots and for the feeding forward of the knotting mechanism. The pile thread withdrawing nippers are first brought from their position of rest (Fig. 7) into the operative position in front of the guide channel 69 (Fig. 9). The open jaws of the nippers 53 grasp the end of the positioned pile thread 64, close on the same, and on returning in the closed condition to the position of rest draw forth a piece of the pile thread. Thereupon a pair of shears 72 (Fig. 8) are swung in from the side into a position in front of the guiding channel 69 and cut off a piece of the pile thread. In the meantime other parts of the mechanism have separated two warp threads, into which the severed piece of pile thread is to be knotted, from the remaining warp threads, and have brought the same into the required position for the tying of the knot. The knotting pincers proper are now brought into action and knot the severed piece of pile thread into the warp threads. For all these steps of the process knotting mechanism according to any one of the known types may be used. After the knot has been drawn tight the eccentric sheaves 37 and 39 come into operation in the above-described manner and, by means of the fixed and movable advancing feet 31 and 32, feed the knotting mechanism and the entire system running on the rails 14 and 15 forward to the extent of the breadth of a knot. As soon as the depressed key 67 and the setting lever 56 pertaining thereto return to the position of rest (Fig. 7) the motor is switched off or the clutch disengaged.

Both the depression of the key 67 and also the mechanical process of knotting and of feeding forward the knotting device can be carried out at high speed. The actual time-consuming operation in hand-knotting, namely the knotting-in of the tufts, is eliminated, and the independently acting knotting device requires for the making of a knot only a fraction of the time required in hand-knotting. The depression of the key 67 by hand and the positioning of the pile threads can be carried out at a speed which is not less than and may even be greater than when the setting of the pile threads is effected by means of a jacquard card. It will be evident that the actuation of the setting levers 56 could also be carried out mechanically by means of a jacquard card or the like.

The selection of the successive pile threads 64, that is to say the actuation of the key-board 67, when the same is performed by hand, is carried out with the help of a pattern drawing (point paper draught) of the

carpet manufactured. This pattern sheet is spread out in a suitable frame above the slay 24, so that it is readily legible for the operator.

The pattern of a carpet or the like is as a rule of such a nature that, during the making of a row of knots, there is only seldom a single knot of the same colour to be knotted; as a rule two, three or more, and even often a large number of knots of the same colour follow in succession. When two or more knots of the same colour are to be made in succession, the operator holds the key 67 concerned in the depressed condition until the series of similarly coloured knots has been completed in one uninterrupted working phase. Each of the keys 67 or each of the setting levers 56 can, however, be fitted with a known type of locking device which retains the said key or lever in the operative position (Fig. 8) until acted upon by a special releasing impulse which returns it to the position of rest (Fig. 7). This releasing impulse is preferably derived from the keys 67 or setting levers 56 themselves, the arrangement being such that the depression of one of the keys 67 causes the setting lever last brought into the operative position (and held in this position during one or more operating cycles) to be returned to the position of rest. Every key and setting lever on actuation thus returns the setting lever occupying the operative position back into the inoperative position (Fig. 7). Mechanisms of this kind in connection with key-controlled apparatus are already known. The operator therefore has nothing else to do but to follow with the eye the row in the pattern drawing to be worked, and at each alteration of the pile thread colour to depress the key 67 applying to the new colour.

In the form of construction of the invention shown in the drawings the system of key levers 65 is mounted at the side of the frame K which carries the knotting mechanism. In order to provide the necessary space both for this system and for the system of setting levers 56 the links 34 and 35 are cranked, as shown in Figs. 4 and 5. It will be clear, however, that the key-board 67 can be turned 90°, so that it is positioned in front of the operator in the manner of the key-board of a typewriter.

After the completion of a transverse row of knots the knotting device and the whole of the mechanism running on the rails 14 and 15 are tilted slightly in the direction of the arrow I (Fig. 4), so that the advancing feet 31 and 32 are brought out of engagement with the reed 29. In order to retain this entire system in this position the frame K is provided with a catch 75 (Fig. 4) which can be hung on a ledge 76 on the front guide rail 15, and thus retains the locking mechanism out of engagement with the reed 29.

Now the framework consisting of the arms 13 and the rails 14 and 15 can be lifted by means of the system of rods 17-21 shown in Fig. 1, so that the entire knotting mechanism is lifted out of the track of the slay 24. The shed is then formed, the weft inserted, and the blow of the slay carried out, all of which can be performed by hand or mechanically.

The knotting device proper, its driving mechanism, the mechanism for the feeding forward of the knotting device, the pile thread setter, as also the driving motor if such be employed, and the bobbin carrier constitute, as will be seen from the drawings and will be clear from the preceding description, a complete and self-sufficing system which is perfectly independent of the loom. This system runs on rails 14 and 15, can be manufactured as an independent unit, and can be mounted on any loom which is suitable for carpet knotting. For this purpose the loom requires no alterations except for the attachment to its framework of the two uprights 11 (Fig. 1) together with the frame consisting of the cradle-arms 13 and the rails 14 and 15 and adapted to be raised and lowered.

In order that, when the knotting apparatus is driven by a motor which participates in the feeding movement, the working of the plant is not necessarily brought to a standstill when the motor is out of order a crank or hand wheel 170, see Fig. 2 can be provided on the main shaft 36 (Figs. 6 and 7); the operator then actuates the setter (keyboard 67) with one hand and turns the shaft 36 with the other hand.

In the form of construction of the invention shown in the drawings there is mounted on the loom only a single knitter which works over the entire breadth of the loom. It is however equally possible to arrange several knitters of the type shown in Figs. 2-9 in connection with one loom; in this case the knitters run on the same rails 14 and 15 which traverse the entire breadth of the loom. When the loom is hand-operated each knotting device is tended by one person, and the separate knitters are disposed at such distances from each other (approximately half a metre to a metre) that the different persons operating the separate key-boards have room to sit next to each other. In this case either a separate driving motor is allotted to each knitter or all the knitters are driven from one single driving shaft, through the intermediary, however, of clutches adapted to be engaged and disengaged in dependence on the actuation of the pile thread setting devices of the single knitters separately, so that in any case the knitters work independently of each other and therefore at high speed.

I claim:—

1. In a device for the manufacture of

knotted carpets and the like with Smyrna or Persian knots, having a mechanism for forming the knots and means for feeding forward the knotting device and nippers for withdrawing pile threads, a series of thread setters associated with the pile threads and adjustable independently of each other within the grasping range of said nippers, actuating means for the knotting mechanism being set in motion by the adjustment of one of said thread setters within the grasping range of said nippers.

2. A device as described in claim 1 comprising means for driving the entire mechanism for forming the knots and feeding the knotting device, said means being actuated by the operation of any one of said thread setters.

3. A device as described in claim 1 comprising a motor for driving the entire mechanism for forming the knots and feeding the knotting device, said motor being actuated by the operation of any one of said thread setters.

4. A device as described in claim 1 in which said thread setters are constructed as levers and mounted in the manner of typewriter levers, thereby bringing the pile threads which are to be knotted into exactly the same position in front of said nippers by a swinging motion of said levers.

5. A device as described in claim 1 in which said setting gears are designed as double-armed levers and key levers adapted to actuate said double-armed levers; the actuation of said key levers thereby causing the selection of the pile thread that is to be knotted at a certain time and the proper setting thereof in front of said nippers.

6. A device as described in claim 1 in which said setting gears are designed as double-armed levers and key levers adapted to actuate said double-armed levers; the actuation of said key levers thereby causing the selection of the pile thread that is to be knotted at a certain time and the proper setting thereof in front of said nippers; said setting gears being provided with a thread-guiding eye at each end and a braking spring for one of said eyes.

7. A device as described in claim 1 having a reed and a carriage for transporting the pile thread setter and the knotting device, said reed serving as ratchet bar for feeding forward said carriage.

8. A device as described in claim 1 having a reed and a carriage for transporting the pile thread setter and the knotting device, said reed serving as ratchet bar for feeding forward said carriage, said carriage being provided with feet adapted to be alternately brought into and out of engagement with said reed for feeding the carriage forward.

9. A device as described in claim 1 having a reed and a carriage for transporting the pile

thread setter and the knotting device, said reed serving as ratchet bar for feeding forward said carriage, said carriage being provided with feet adapted to be alternately brought into and out of engagement with said reed for feeding the carriage forward, the stroke of one of said feet being variable in order to alter the spacing of the reed and consequently the setting of the knots.

10. A device as described in claim 1 having a reed and a carriage for transporting the pile thread setter and the knotting device, said reed serving as ratchet bar for feeding forward said carriage, said carriage being provided with feet adapted to be alternately brought into and out of engagement with said reed for feeding the carriage forward; a batten adapted to support the dents and stiffen the reed, said batten extending along the points of engagement of said feet.

20 11. A device as described in claim 1 adapted for looms with a horizontal warp, and having a reed and a carriage for transporting the pile thread setter and the knotting device, said reed serving as ratchet bar for feeding forward said carriage; rails adapted to support said carriage, said rails being disposed parallel to the weft and adapted to be slidable in the direction of the weft and tilttable in the direction of the warp.

30 In testimony whereof I have affixed my signature.

FRANZ HUEBNER.
